AUTOMATIC WATER HEATER

John C. White and Roy W. Miller, Madison, Wis., assignors to The Hydro-Heater Corporation, Madison, Wis., a corporation of Wisconsin

Application April 15, 1932. Serial No. 605,436

5 Claims. (Cl. 137—111)

This invention pertains to water heating devices which employ steam for the heating of the water and which are intended particularly for shower bath use or other uses where quite accurate control of the water temperature is necessary.

In many places, such as public institutions, there is plenty of steam available which can be employed for heating of water for showers and which when utilized in accordance with this invention can be used in installations which are low in first cost in comparison to storage tank systems and which will have a minimum of maintenance difficulties and expense.

15 Among the objects of this invention are to provide a water heater employing steam and normally controllable in its usual operation by one valve only; to provide in a water heater of this character simple and effective means for 20 varying the output temperature of the water from a fixed maximum; to provide positive means for preventing a maximum water temperature from being exceeded in such a heater; and to provide other various objects and advantages which will hereinafter more fully appear.

In the drawings, Fig. 1 is an elevation of apparatus made in accordance with this invention.

Fig. 2 is a longitudinal central sectional view 30 of a diaphragm controlled valve forming a part of this invention.

Fig. 3 is a sectional view on the line 3—3 of Fig. 2 showing the means for adjusting the combining tube.

35 Fig. 4 is a longitudinal central sectional view of a modified form of the invention while,

Fig. 5 is a side elevation of the modified form shown in Fig. 4.

Referring now to the drawings, the diaphragm 40 controlled valve consists of a yoke 1, a diaphragm 2 which is clamped against the yoke and is sealed thereagainst by a dome 3 having a water inlet 4. The diaphragm is clamped between a small piston 5 and a washer 6, the latter being held by a pair of lock nuts 7 and 8 threaded on a stud 9, the opposite end of which has a head 11 against which the piston rests. A set screw 12 may be advanced in the dome toward the stud to determine the limit toward 45 which the diaphragm may be distended in that direction while a cap screw 13 is employed to close the threaded aperture in which the set screw moves.

50 Adjacent the head of the stud is a needle valve shaft 14, one end of which 15 is shaped

to provide the needle valve and the other end of which is threaded to receive an adjusting nut 16. Below the adjusting nut is a spring retaining member 17 against which the compression springs 18 and 19 rest, their opposite ends embracing bosses 21 and 22 provided at the other end of the yoke 1. A suitable packing gland generally designated as 23 is provided about the needle valve where it extends into a steam chamber 24. The inlet 25 serves to admit steam into the chamber 24. A valve seat 26 cooperates with the needle valve to regulate the steam which is injected into the water.

Water into which the steam is injected flows through the inlet 27 into the chamber 28 and 70 into the upper end of a combining tube 29, thence into the pipe 31 to a temperature control valve 32. By advancing or retracting the combining tube relative to the needle valve seat the proportions of the steam and water may be varied. The combining tube is exteriorly threaded where it passes through the wall of the casing 30 and also is provided with a worm wheel 33 fixed thereon which may be rotated by means of a worm screw 34 manually rotatable by means of the handle 35.

75 A control pipe 36 is connected with the pipe 31 and with the inlet 4 of the diaphragm dome. If desired, for facilitating regulation, a pressure indicating gauge 37 may be installed as shown. Suitable stop valves 38 for the steam and 39 for the water may also be provided to be used only in case of adjustment or repair of the unit.

80 The device shown in Figs. 1, 2 and 3 operates as follows: Assuming that the steam pressure is perhaps 40 pounds and the water main pressure is about 20 pounds, both the water and steam are turned on and all valves opened. It is first necessary to adjust the device, after which no further adjustments will ordinarily be necessary. The temperature control valve 32 will be throttled down until the maximum desired water flow for the showers or other fixtures is attained. This may be noted on the pressure gauge as showing about perhaps 10 pounds. The combining tube 29 will then be adjusted toward or away from the needle valve seat until the desired water temperature at the outlet is attained. For shower bath use this might be 105° F. There will probably be some change in the pressure at the outlet due to the altering of the injecting action at the steam jet and this will be observable at the pressure gauge. The temperature control valve will then be operated to correct the adjustment of the outlet pressure. The combining tube and temperature control valve 100

100

105

110

can further be adjusted until the desired temperature and outlet pressure is obtained.

The set screw 12 may then be adjusted if necessary to limit the opening of the needle valve so that the correct temperature may be attained at the rate of flow determined as desirable by the temperature control valve. It may be necessary to adjust the compression springs also to cause them to hold the needle valve open and against the set screw during this maximum water flow. This adjustment is easily accomplished by means of the nut 16. The device is then ready to operate and the temperature control valve may thereafter be used for stopping and starting the water flow and also for varying the water temperature downwardly from the predetermined maximum. It will appear clear that partial closing of the control valve 32 will increase the water pressure in the dome 25 above the diaphragm and hence cause the needle valve to approach its seat, thus reducing the amount of steam being utilized. Complete closing of the control valve should so increase the pressure in the diaphragm dome that the needle valve will fully seat and cut off the steam completely, which will happen if the compression springs are properly adjusted. Further opening of the control valve beyond the position it occupied when the system was adjusted for normal operation will decrease the dome pressure but no additional steam will be admitted because the set screw 12 will limit the opening of the needle valve. Hence increased flow of water beyond the normal flow will only result in a lowering of the water temperature. In no event can the water temperature exceed the predetermined desired temperature. Hence the equipment can be used in shower bath installations without danger to the user and only one valve, the control valve 32, is needed for stopping and starting the water flow and regulating its temperature.

The modified form of the invention shown in Figs. 4 and 5 is constructed as follows: The diaphragm 41 is gripped between a dome 42 and a cylinder head 43, the upper enlarged end of which is open to the atmosphere, while the reduced portion 44 of the cylinder head contains a piston 45 which is slidable therein and directly connected through the shaft 46 to a piston 47. The piston 47 is fastened by means of a threaded screw 48 to a pair of washers 49 and 51 between which is clamped the diaphragm. The usual adjusting nuts 52 lock the diaphragm on the screw. A stop screw 53 limits movement of the diaphragm in one direction while a cap screw 54 closes the stop screw aperture. A pair of compression springs 55 are mounted as shown to urge the piston 47 in the direction shown. Since the lower end of the piston 45 is exposed to the steam pressure in the steam chamber 57, the steam pressure acting on the piston furnishes part of the resistance to the water pressure acting on the diaphragm 41, hence only light springs 55 are needed to give a good balance and a quick response.

The piston 45 carries the needle valve, one end of which serves to lock the piston to the shaft 46, and the other end is fashioned in the shape of a needle 56.

The needle valve extends through a steam chamber 57 having an inlet 58 and seats in the valve seat 59. A water inlet 61 admits water into the water chamber 62 from whence it flows into the upper end of the combining tube 63 and

thence through the chamber 64 and pipe 65 to the place of use. The combining tube is surrounded by suitable packing glands 66 and 67 as shown and is threaded into the water chamber housing 68 in such a way that rotation of the tube will cause it to approach or retract with reference to the needle valve seat, thus serving to alter the proportions of steam and water which are mixed. The combining tube may be rotated in any suitable manner but for the sake of simplicity it is provided with a pair of flat surfaces 69 by means of which it can be gripped with a wrench very readily.

To take care of leakage which may occur alongside of the piston 45, there is provided an outlet pipe 71 which runs to waste.

In order that the outlet pressure of the water may be employed to control the diaphragm, a control tube 72 is connected as shown. Hence the outlet water pressure in pipe 65, communicated through the control tube, will serve to proportion the steam and water up to a certain temperature limit and at that point further admission of steam will be prevented by setting the stop screw 53 to prevent further lift of the diaphragm even though the water pressure in the dome continues to decrease.

The modified form shown in Figs. 4 and 5 is particularly useful in large shower bath installations where several dozen shower heads 105 are to be supplied from one temperature regulating device.

In a unit of this size for convenience in mounting, it is sometimes found advisable to mount the unit on a base 73 which can be then bolted to a wall and the pipes thereafter attached. The adjustment of this modified device requires no particular explanation in view of the description of the form shown in Figs. 1 and 2.

In the operation of both forms of the invention even though cold water may be drawn from the water supply to some other place of use during the operation of these heating devices, this mixing device will not be affected or, if at all, scarcely noticeably due to the fact that a sufficient margin of pressure difference will ordinarily be maintained between the water inlet and water discharge and also due to the fact that the steam exercises an important control effect because of its injecting action.

It should be understood that this invention while illustrated herein in two embodiments is yet susceptible of being employed in other forms which may differ in various details from the present disclosure also remaining within the scope 130 of the appended claims.

Having shown and described our invention, we claim:

1. In a water heating device, means connected with a source of steam and a source of water for mixing the two, and means controlled by the pressure of the water on the discharge side of said mixing means for varying the proportions of steam and water so mixed.

2. In a water heating device, means connected with a source of steam and a source of water for mixing the same, and a pressure controlled valve actuated by variations in pressure of the water on the discharge side of said mixing means for regulating the amount of steam introduced into said mixture.

3. In a water heating device, means connected to a source of steam and a source of water for mixing the two and a diaphragm controlled valve actuated by variations in the pressure of the

water on the discharge side of said mixing means for regulating the amount of steam added to said mixture.

4. The combination of a water heating device and a pipe for conducting the heated water to a place of use comprising means connected with said pipe and a source of steam and a source of water arranged for combining the two, a pressure actuated valve for controlling the admission of steam to said mixing means, a conduit connecting said pipe at the discharge side of said mixing means operatively to said valve and another valve in said pipe beyond said conduit for stopping and starting the water flow to point of use and whose regulation between open and closed position varies the pressure on said pressure actuated valve.

5. In a water heating device, a casing having a steam chamber and a steam inlet therefor, a valve seat in one wall of said chamber and a valve

therefor, a water chamber and water inlet therefor, a threaded aperture in one wall of the water chamber and a combining tube exteriorly threaded extending through said aperture toward the orifice of said steam valve seat, means for rotating said tube on said threads toward or away from said valve seat, a pressure chamber having a flexible diaphragm forming one wall thereof and means operatively connecting said diaphragm to said steam valve to seat the same upon distention of the diaphragm, said combining tube being adapted to receive a mixture of steam from said valve and water from said water chamber for delivery to a point of use, and a pipe connected with the delivery side of said tube and said pressure chamber for subjecting said pressure chamber to the pressure of the water so heated by said steam.
